HYDROTHERAPY MASSAGE UNIT

Ruth Kulisch geb. Klages, Schwalbenstr. 7,
2902 Rastede, Germany

Filed July 5, 1973, Ser. No. 376,840

Claims priority, application Germany Jan. 5, 1973

Term of patent 14 years

Int. Cl. D24—04

U.S. Cl. D83—1 C

FIG.1

FIG.2

FIG. 3

FIG. 1 is a perspective view of a hydrotherapy massage unit showing my new design;

FIG. 2 is a bottom view of a portion of the unit shown in FIG. 1 thereof; and

FIG. 3 is a bottom rear perspective view of a portion of the unit of FIG. 1 thereof.

The design is intended for use on air bubble devices and their associated accessories.

I claim:

The ornamental design for a hydrotherapy massage unit, substantially as shown and described.
